UNITED STATES PATENT OFFICE.

ROBINSON W. SHELBOURNE AND JAMES H. SUBLETT, OF BLANDVILLE,
KENTUCKY.

PLOW.

SPECIFICATION forming part of Letters Patent No. 377,646, dated February 7, 1888.

Application filed August 4, 1887. Serial No. 246,148. (No model.)

To all whom it may concern:

Be it known that we, ROBINSON W. SHELBOURNE and JAMES H. SUBLETT, both residents of Blandville, in the county of Ballard 5 and State of Kentucky, have invented certain new and useful Improvements in Plows; and we do hereby declare that the following is a full, clear, and exact description of the invention, which will enable others skilled in the 10 art to which it appertains to make and use the same, reference being had to the accompanying drawings, which form a part of this specification, and in which—

Figure 1 is a perspective view of our new 15 and improved plow. Fig. 2 is a side view of the same, taken from the land side thereof. Fig. 3 is a perspective view of the inner or form plates of the plow with the mold-board and cutter removed from the same; and Fig. 20 4 shows a blank from which two of the metal form-plates, which are bent to form the inner body of the plow, are cut.

The same letters of reference indicate corresponding parts in all the figures. 25 Our invention consists in a new and improved plow, which will be hereinafter fully described and claimed.

Referring to the several parts by letter, A indicates the metal plate out of which the landside B and the flange C are formed, on which the mold-board is bolted, the blank or pattern A being cut with suitable shears out of a sheet or plate of metal, as shown in Fig. 4 of the drawings, the blanks A being so shaped that 30 they may be cut out of the metal plate without any waste, as clearly shown in the said view, except that of the small squares a^2 , where the opening for the upright or standard of the plow is left. These blanks A are then split a 35 little at a^2 , at the top and bottom of what may be called the "throat" of the plow form, and are then bent into the requisite form by placing each blank (the blanks being formed of a steel plate) while hot over a suitably- 40 shaped matrix and forcing a convex angular die of sufficient weight down over the hot steel plate, which forms the said plate to the desired shape, (shown in Fig. 3 of the drawings,) when the landside B, with its curved longitudinal 45 flange C, is finished and ready to be embodied 50 in the plow by having the mold-board and the

cutter, with the separate point, secured to it, together with the standard, as hereinafter described.

E indicates the mold-board of our improved 55 plow, which is also constructed out of steel plates susceptible of high temper, which is given to these outer plates forming the mold-board, which come in direct contact with the soil. The wing of the mold-board is preferably 60 of the shape and curvature shown in the accompanying drawings. The upper part or wing, F, of the mold-board is bolted to or upon the flange C, while the lower section or point of the mold-board is bolted both to the lower 65 end of this flange C and to the lower forward end, B', of the landside, being formed on its inner side or edge with the downwardly-bent flange G', inside of which the said point of the landside extends and to which it is bolted. 70

H indicates the cutter of our new and improved plow, which is formed of a highly-tempered steel plate, which is bolted to the landside B by three bolts, I, when the cutter-plate is formed in one piece; as shown in full lines 75 in the accompanying drawings, so that the entire cutter may be removed, detached, and changed for repair without stopping the plow to go to the shop by merely loosening the three bolts; or, if preferred, we can construct the 80 cutter in two pieces, dividing the cutter-plate on the slanting or inclined dotted line shown in Fig. 2 of the drawings, in which case the rear section of the cutter-plate is secured to the landside by three bolts, while the forward 85 section, which is formed with the beveled and sharpened cutting-edge, is retained in place against the landside by two bolts only, so that it can be readily removed to be sharpened, &c., merely by loosening the said two bolts. 90 The forward upper part of the cutter-plate extends out straight in advance of the inner side of the mold-board of the plow, as shown, its forward inclined edge, H', being beveled and sharpened for its entire length, to adapt it to 95 cut readily and easily through sods, roots, &c., while the upper rear edge of the cutter-point K is welded to the forward end of the landside and the forward end of the inner flange, G', of the lower part of the mold-board, 100 so as to face with the cutter-plate—that is to say, lies in the same vertical plane with the

cutter-plate and forms, practically, an extension of the same. The upper rear edge of this point K is beveled and sharpened and forms a continuation of the cutting-edge of the cutter-plate, joining squarely with it, and thus brings the cutting-edge down as close or near as is advantageous to the point of the plow.

L indicates the upright standard of the plow, which is bolted to the inside of the landside, 10 and to which the upper end of the cutter-plate is also bolted, this standard being preferably formed of a straight flat metal bar, as shown, although its precise form may of course be altered, if desired.

15 It will be seen that we thus construct a plow of steel plates, the outer plates, which come in direct contact with the soil, being given a high temper, while the under or form plates may be left soft or in their annealed condition, thereby 20 forming a plow which is capable of resisting the greatest force or strain from the toughness of these unhardened inner plates, while the hardened outer plates, which come in direct contact with the soil, are rendered unsusceptible to wear, so that our new and improved 25 plow as thus constructed is exceedingly durable and will last for a very long time under the most severe usage.

The cutter-point K is secured by two bolts, 30 and can be removed for repair or sharpening by merely loosening these two bolts, and can thus be replaced in the field with but little delay.

From the foregoing description, taken in connection with the accompanying drawings, the 35 construction and many advantages of our invention will be readily understood. It will be seen that we succeed in constructing a plow which is exceedingly strong and durable and 40 very efficient in its operation. The operative parts can all be removed for repair in a short time and with little trouble, and the cutting-edges can be sharpened and the several parts replaced, as described.

45 Our new and improved plow, with its improved cutter, is applicable to any kind of work, from coltering new ground with a heavy team to siding spring corn with one horse, the projecting cutter-blade throwing all of the dis-

placed clods onto the wing of the mold-board, 50 the inclination of which throws the clods to one side sufficiently far to be out of the way, doing the work in a superior manner and without attention from the plowman.

Our new and improved plow is exceedingly 55 strong and durable, is fully susceptible of repairs, and is exceedingly effective in its operation, lessening the draft materially, from twenty-five to thirty-three per cent.

When using our improved plow in turf, tobacco stubble, or in any such work, it turns the earth or soil without displacement, except on the mold-board side or turning side of the plow, so that in siding young corn or other small plants the dirt is thrown entirely away 65 from it, so that there is no danger of covering the small and tender plants with clods thrown or pushed to the wrong side by the plow, which never occurs.

Having thus described our invention, what 70 we claim, and desire to secure by Letters Patent of the United States, is—

1. A blank for forming the landside and flange of a plow, consisting of a rectangular plate having a split at one corner and an open- 75 ing or square recess at the opposite corner, the end of the plate having the recess being extended to form the bar, substantially as shown and described.

2. In a plow, the combination of a back portion consisting of one piece forming the landside or bar and a curved portion bent laterally from said landside portion, said piece being split at its lower point, a mold-board secured to the upper part of the curved portion, 85 a share secured to the lower part and to the point of the landside, a plate or colter secured to the landside, and a standard, substantially as shown and described.

In testimony that we claim the foregoing as 90 our own we have hereunto affixed our signatures in presence of two witnesses.

ROBINSON W. SHELBURNE.
JAMES H. SUBLETT.
